INVENTOR
JOHN J. DONOVAN

BY Henry Strong, Townsend & Loftus
ATTYS.

UNITED STATES PATENT OFFICE.

JOHN J. DONOVAN, OF OAKLAND, CALIFORNIA.

LATCH FOR AWNING-TYPE WINDOWS.

Application filed June 10, 1925. Serial No. 36,079.

This invention relates to a window latch which is particularly adapted for use in connection with so-called awning type windows such as described and claimed in a United States Letters Patent, No. 1,541,123, entitled Swinging windows, issued to me on June 9, 1925.

In general, the window disclosed in the said patent comprises a pair of sashes mounted in a frame in offset relation to give a double hung effect. These sashes are pivotally and slidably connected with the frame by mechanism which permits them to be operated in unison or separately.

In this type of window a certain amount of play is present in the operating mechanism, and permits a certain amount of relative movement between the windows. Due to this fact, the meeting rails of the sashes do not always remain tightly in abutment, which results in rattling and other disagreeable effects.

It is the object of the present invention to provide an improved latch mechanism for windows of the type referred to, which will automatically latch or unlatch when the sashes are operated from the interior of the building in which the window is placed, and which will effectively latch the meeting rails of the sashes together to prevent relative movement between the sashes and also act, to a certain extent, in preventing opening of the sashes from the exterior of the building.

In carrying out this object, I provide a vertically pivotal keeper which is mounted on the lower rail of the upper sash and which is adapted to engage a keeper plate mounted on the adjacent rail of the lower sash. The peculiar relative movement occurring between the sashes when they are swung open automatically disengages the keeper from the keeper plate. Likewise, when the sashes are closed, the keeper automatically becomes engaged with the plate and securely latches the sashes against opening from the exterior of the building.

One form which the invention may assume is exemplified in the following description and illustrated by way of example in the accompanying drawings, in which:

Fig. 1 is a view in vertical section through

a window frame disclosing the latch mounted on the sashes.

Fig. 2 is an enlarged view of the latch structure in side elevation.

Fig. 3 is a view of the same in plan.

Referring more particularly to the accompanying drawings, the latch which embodies the present invention is here shown as mounted on a window structure which comprises a frame 10, and a pair of swinging sashes 11. These sashes as shown in Fig. 1 are offset with relation to each other so that the sides of the contiguous rails 12 of the sashes abut. The upper end of each sash is fitted with a pair of horizontal extending trunnions 14 which are slidably received in vertical grooves 15 formed in the faces of the jambs of the frame 10. A pair of fulcrum links 16 is pivotally connected to the sashes intermediate the ends of each sash and to the jambs. This mounting of the sashes permits opening thereof by merely pushing outwardly on their lower ends.

In order that the sashes may be operated in unison, the trunnions of the sashes are connected by a connecting bar 17. This bar may be detachably connected with the trunnion of either sash and operated to disconnect the sashes in order that they may be operated separately. This, however, does not form a part of the present invention, it is merely shown and described so that the operation of the latch with which the present application is more particularly concerned may be more fully understood.

It is seen that to open the sashes it is only necessary to push outwardly on the lower end of the lower sash. This causes the lower ends of the sash to swing outwardly and the upper ends of the sash to travel downwardly in a straight path due to the provision of the trunnions and the vertical grooves in which they are slidably mounted. This peculiar movement of the sash is utilized to automatically unlatch and latch the latch mechanism, generally indicated at 18, when the windows are opened and closed.

The latch mechanism comprises a substantially U-shaped clip 19 which is disposed vertically and which is formed with toe flanges 20 by which it may be secured to the

upper surfaces of the lower rail of the upper sash interiorly of the pane. A keeper 21 is provided, the outer end of which extends between the sides of the clip 19 and which is pivotally connected thereto by a horizontally disposed pivot pin 21^a. This pin is secured at its ends in the sides of the clip 19. This mounting of the keeper permits its to oscillate vertically.

10 To limit the downward movement of the keeper, its inner end is provided with a lug 22 which is adapted to abut against the outer end of the clip 19. The inner end of the keeper 21 is hooked so that it may engage a keeper plate 23 which is secured on the upper face of the top rail of the lower sash, which is disposed flush of the top surface of the lower rail of the upper sash when the windows are closed. This keeper plate 15 may be secured in place with screws.

15 The keeper 21 is normally held engaged with the keeper plate 23 by an expansion spring 24 which is inserted in a recess formed in the keeper and interposed between the latter and the top of the U-shaped clip 19.

20 In operation of the latch, when the lower end of the lower sash is moved outwardly its upper end simultaneously moves downwardly and moves out of engagement with the keeper 21. This is also true if the sashes are moved in unison as the lower end of the upper sash swings outwardly the upper end of the lower sash moves downwardly and consequently disengages the keeper from the keeper plate.

25 When the sashes are closed the inner end of the keeper strikes a cam surface 25 on the keeper plate and rides over the latter, as the rails of the sashes are brought together, until its hooked end engages the inner end of the keeper plate, thus latching the sashes in position.

30 From the foregoing it is obvious that the latch automatically releases when the sashes are opened from the interior of the building and that it automatically latches the windows when the latter are closed.

35 The latch will effectively prevent opening of the windows from the exterior of the building because no purchase can be obtained exteriorly of the sashes to open them.

40 While I have shown the preferred form of my invention, it is to be understood that various changes in its construction and operation may be made by those skilled in the art without departing from the spirit of the invention as defined in the appended claims.

45 Having thus described my invention, what I claim and desire to secure by Letters Patent is:

50 1. A latch for awning type windows comprising latch means carried by contiguous rails of the sashes and adapted to latch the same together, said latch means being adapted to automatically release when the sashes

are opened and to automatically latch the same together when closed.

55 2. A latch for awning type windows comprising a pivotal keeper carried by the rail of one sash, a keeper plate carried by the adjacent rail of the other sash and with which the keeper is adapted to engage to latch the sashes together, said keeper and keeper plate being adapted to automatically disengage when the sashes are opened and to automatically engage when the sashes are closed.

60 3. A window latch for awning type windows comprising a vertically pivotal keeper mounted on the rail of one sash, a fixed keeper plate mounted on the rail of the adjacent sash for co-operation with the keeper, said keeper and keeper plate being adapted to automatically engage and latch the sashes together when the windows are closed and to automatically disengage when the windows are opened.

65 4. A window latch for awning type windows comprising a vertically pivotal keeper mounted on the rail of one sash interiorly of the pane and projecting inwardly, a keeper plate mounted on the rail of the adjacent sash for co-operation with the keeper, a spring tending to maintain said keeper in engagement with the keeper plate, said keeper and keeper plate being adapted to automatically engage and latch the sashes together when the windows are closed and to automatically disengage when the windows are opened.

70 5. A latch for awning type windows comprising a vertically pivotal keeper mounted on the lower rail of the upper sash interiorly of the pane and projecting inwardly, the inner end of said keeper being hooked, a spring tending to force the inner end of said keeper downwardly, a keeper plate on the top rail of the lower sash and over which said keeper is adapted to hook whereby when said windows are opened said keeper plate will automatically disengage from said keeper, a cam surface on the keeper plate adapted to be engaged by the inner end of the keeper when the windows are being closed to guide the keeper whereby it will automatically engage with the keeper plate and latch the windows together when the latter are closed.

75 6. A latch for awning type windows comprising a U-shaped clip adapted to be vertically disposed and secured on the top surface of the lower rail of the upper sash, a keeper having its outer end extending between the sides of the clip and pivoted thereto whereby it may swing vertically, the inner end of said keeper being hooked, a spring interposed between the top of the clip and the keeper constantly tending to force the inner end of said keeper downwardly, a lug on the outer end of said keeper engaged by the clip to limit the downward movement of the inner end of the keeper, a keeper plate adapted

to be secured to the top surface of the upper rail of the lower sash and over which the hooked end of said keeper hooks, whereby when said windows are opened said keeper plate will automatically disengage from said keeper, a cam surface on said keeper plate adapted to be engaged by the inner end of the keeper when the windows are being closed to guide the keeper into latching engagement with the keeper plate and thereby ¹⁰ latch the sashes together when the same are closed.

JOHN J. DONOVAN.
